UNITED STATES PATENT OFFICE.

WILLARD EARL, OF ONTARIO CENTRE, NEW YORK.

NIPPLE-WRENCH.

SPECIFICATION forming part of Letters Patent No. 664,244, dated December 18, 1900.

Application filed May 4, 1900. Serial No. 15,472. (No model.)

To all whom it may concern:

Be it known that I, WILLARD EARL, a citizen of the United States, residing at Ontario Centre, in the county of Wayne and State of New York, have invented a new and useful Improvement in Nipple-Wrenches, of which the following is a specification.

My invention relates to nipple-wrenches, and has for its object to produce a device of this kind which shall be simple, cheap, and efficient; and it consists in the improved construction and novel arrangement of parts of the same, as will be hereinafter more fully set forth.

In the accompanying drawings, in which the same reference-numerals indicate corresponding parts, Figure 1 is a perspective view of my improved nipple-wrench. Fig. 2 is a longitudinal sectional view of the same, and Fig. 3 is an end view.

Referring more particularly to the drawings, 1 indicates the main portion of my clamp, which is formed substantially U-shaped from a flat piece of steel or suitable material. The free end of each of the legs 2 is bent inwardly to form a jaw 3, one of which is recessed from near the center to the end, the inner end of the recess being preferably slightly shouldered and the bottom of the recess 4 being inclined, as shown at 4, so that when the straight portions are in contact with each other the remaining portion of the jaws will form a substantially V-shaped recess which is adapted to engage with the nipple and hold the same against rotation.

The bent or bottom portion of the device is preferably cutaway upon one side, as shown at 5, substantially to the depth of the recessed portions 4 at the opposite end of the wrench.

Two winged edges project upwardly at the curve of the wrench at a slight distance from each other, between which is seated the spoke of the wheel when the wrench is in position. The wings may be formed integral with the

main portion of the wrench, or they may be formed from a separate piece of material 7, which is slit longitudinally at one end and has its central portion bent from between the wings and doubled upon the remaining portion, so as to engage with the wrench at the bend and hold the wings in position.

Each of the legs is provided with a perfora-

tion 8 near its free end, through which is passed a bolt 9, one end of which is rigidly secured to one of the legs—as, for instance, by means of a jam-nut 10—and the end which projects through the other leg is provided with a winged nut 11. The outer portions of the wings may be joined together at a suitable distance from the nut proper, so as to form a stop to engage with the outer end of the bolt and limit its further movement, thereby preventing the nut from being screwed in so far as to damage the jaws of the wrench or the legs by screwing the nut in too far.

In using my improved nipple-wrench the jaws are opened a sufficient distance to engage with the nipple by unscrewing the winged nut, after which the recessed portions of the jaws are caused to clamp the nipple between them by screwing up the winged nut against the leg. By making the recess V-shaped the wrench can be more easily entered upon the nipple, and it may be adapted for use upon nipples of different sizes. When it has been secured in position in this manner, the spoke will extend between the wings and hold the wrench in proper position upon the nipple. After the wrench has been thus secured in position the screw through the tire may be manipulated in the ordinary manner and the wheel turned around to determine the proper adjustment of the tire without removing the wrench. As soon as a spoke has thus been adjusted the wrench can be readily removed by unscrewing the winged nut, when the elasticity of the bend will automatically open the jaws and permit the removal of the wrench and place it in condition for insertion upon another spoke.

Although I have shown what I consider to be the most desirable form of constructing my improved nipple-wrench, yet I reserve to myself the right to make such changes and alterations therein as will come within the scope of my invention.

Having thus fully described my invention, what I claim as new, and desire to secure by Letters Patent of the United States, is—

1. In a nipple-wrench for bicycles, the combination with a substantially U-shaped body, the free end of each leg of which is bent inward and recessed at one end, and the bent portion of the body is recessed, and means

for forcing the recessed ends of the legs toward each other, substantially as described.

2. In a nipple-wrench for bicycles, the combination, with a substantially U-shaped body portion, the free end of each leg of which is bent inward to form jaws, the inner edge of each jaw at one end being provided with an inclined bottomed recess, and the bent portion of the body is provided with a recess to correspond therewith, and a bolt for engaging with said legs and forcing the jaws toward each other, substantially as described.

3. In a nipple-wrench for bicycles, the combination, with a substantially U-shaped body, the free end of each leg of which is perforated and bent inward to form a jaw, the inner edge of each jaw at one end being recessed, and the bent portion of the body being recessed to correspond therewith, of a bolt se-

cured in the perforation of one of the legs 20 and projecting through the perforation of the other leg, and a winged nut upon the projecting portion of said bolt, substantially as described.

4. In a nipple-wrench for bicycles, the combination, with a substantially U-shaped body, the free ends of the legs of which are provided with coacting recessed jaws, and the bent portion of the body is cut away and provided with two parallel wings at a distance from each other to form a recess therebetween, and a bolt through the free ends of the legs for moving the jaws toward each other, substantially as described.

WILLARD EARL.
